UNITED STATES PATENT OFFICE.

WILLIAM S. MENDEN, OF BROOKLYN, NEW YORK, ASSIGNOR TO MEGOSIN COMPANY, INC., A CORPORATION OF NEW YORK.

MEANS FOR CONTROLLING THE ILLUMINATION OF VEHICLES.

1,135,605.

Specification of Letters Patent.

Patented Apr. 13, 1915.

Application filed December 2, 1913. Serial No. 804,224.

To all whom it may concern:

Be it known that I, WILLIAM S. MENDEN, a citizen of the United States, residing in the borough of Brooklyn, county of Kings, 5 and State of New York, have invented certain new and useful Improvements in Means for Controlling the Illumination of Vehicles, of which the following is a full and clear specification.

10 This invention relates to means for illuminating vehicles and has for its primary object to provide an improved illuminating system for passenger vehicles which travel successively in daylight and darkness, such 15 for example as some of the modern rapid transit subway passenger cars which in some places travel above the ground.

More specifically, the present invention 20 contemplates the provision of suitable means depending upon the movement of the vehicle which carries the illuminating system, for successively energizing and de-energizing the lights at or adjacent the terminal points of the zones of light and darkness.

25 This invention furthermore contemplates certain details of construction, combination and arrangement of parts in an illuminating system for vehicles which will 30 make it possible to accomplish the objects set down in a simple and efficient manner.

Durability of parts and economy in operation also constitute some of the minor objects in invention.

35 Other and further objects will appear in the claims, reference being had to the accompanying drawings in which my invention is exemplified.

In the drawings, Figure 1 is a diagrammatical plan view of an electric circuit for 40 an illuminating system, according to the present invention; Fig. 2 is a diagrammatical plan view of another embodiment of the same; Fig. 3 is a vertical section of the 45 mechanism for automatically controlling the energization and de-energization of the lighting system, parts being shown in elevation; Fig. 4 is a section on the line IV—IV, Fig. 3, parts being shown in elevation; Fig. 5 is a side elevation of the 50 contact wheel on an enlarged scale; Fig. 6 is an axial section of the same; Fig. 7 is a fragmentary detail to be hereinafter referred to.

Referring more particularly to the drawings, in the embodiment shown in Fig. 1 a plurality of car lights 1, 2, 3, 4, 5 are arranged in pairs. Leading from the trolley line 16 is a wire 15 which is connected by a switch 14 to the line wires 12 and 13. 55 These wires 12 and 13 connect the lamps 5, 4, 3, 2 and 1 throughout in parallel series. A line wire 11 which connects the pair of lamps 1 in parallel leads directly from said lamps 1 to an automatic circuit making and breaking instrumentality, designated generally by the reference numeral 10. Leading from the circuit controlling instrumentality 10 is a wire 9 which joins a wire 9' leading to a battery 6, said battery 60 being connected through a wire 7 to the ground line 8. The wire 9' leads from the battery 6 to a line 17 and by a line 17 to a plurality of emergency lights 18 which are arranged in parallel and connected to a 75 wire 19 which is grounded at 20 to ground line 8. Thus it will be seen that when the switch 14 is closed the current passes from trolley line 16 through wires 12 and 13 to lamps 5, 4, 3, 2 and 1, thence by line 11 80 through the circuit making and breaking instrumentality 10 back through line 9 to wire 9', where the current is split, going through battery 6 and wire 7 to ground line 8 and through line 9' to line 17, emergency 85 lamps 18 and wire 19 which is grounded at 20 to ground wire 8. It will be noticed that when the trolley circuit is closed and the circuit making and breaking instrumentality has been operated to close the circuit, 90 all lamps including the emergency lamps will be lighted and continue to burn as long as the current making instrumentality maintains a closed circuit. The circuits are so arranged that the emergency lamps will 95 be lighted at all times either by the trolley current or by the battery current. If by the latter the current will pass from battery 6 through wire 9' to wire 17, lamps 18 to wire 19 which is grounded at 20 to line 8. 100 At night time or in situations generally where there is continual darkness, the circuit controlling instrumentality 10 is undesirable. In order to maintain the current in the circuits just mentioned, a switch 21 is 105 provided in a short circuiting shunt, including the branches 22 and 23 which are connected respectively with the wires 9 and 11.

Suitable fuses 24 are preferably interposed between the switch 14 and the line wires 12 and 13.

According to the embodiment shown in Fig. 2, the trolley line 16 delivers current by a wire 25 provided with a switch 26 to the lamps 27 arranged in a plurality of series, said lamps being connected by a line 28 with the instrumentality 10 for making and breaking the circuit automatically by means to be hereinafter described, which are operated at predetermined points of travel, the operation of the same being dependent upon the movement of the vehicle. The instrumentality 10 is grounded by the line 29 in the ground line 8.

Referring now to Figs. 3 to 7 inclusive, the current controlling mechanism will be described. As shown in Fig. 3, the lead wire 9 enters the trip housing 30 and is connected with the fixed contact 31. The wire 11 is connected to a suitable binding post 32 which is mounted on the outer wall of the housing 30. The fixed contact 31 is adapted to be engaged successively by a plurality of fingers which are constituted by good conductors and insulators alternately. In the present embodiment, fingers are arranged as shown in Figs. 5 and 6, to project radially from a hub 33. Thus in Fig. 5, eight radially disposed arms 34 and 35 are mounted upon the hub 33 and uniformly spaced to form angles of 45°, with each other. It will be noted that the arms 35 are pivotally mounted upon pins 36 which are carried by the hub 33, said arms 35 being yieldably supported at their outer ends by means of the springs 37 which respectively connect each of the movable arms 40 with one of the fixed arms. The fixed arms carry the insulating contacts while the movable arms 35 carry the circuit closing contacts, the springs 37 being adapted to make a sharp break in the circuit to avoid sparking. From an inspection of Fig. 3, it will be noted that the spaced contacts 38 which are carried by the circuit making arms 35 are rounded on their extremities to adapt them to seat within the recess 39 formed 50 within the extremity of the contact 31. The hub portion 33 of the contact wheel is journaled upon a bolt 40 and is provided with an annular recess 41 for the reception of a spring 42 which is interposed between the head of said bolt and the inner end of said recess to yieldingly retain the hub 33 against the boss 43 formed in the wall of the housing 30. By means of this construction, the contact arms are adapted to engage the fixed contact 31 with a resilient action. A ratchet wheel 44 which is carried by the hub 33 of the contact wheel is adapted to be actuated by the spur 45 of a pawl 46 (see Fig. 4), said pawl being

pivotedly mounted at 47 upon a reciprocable bar or lever 48. Suitable bearing straps 49 are provided for the support of the bar or lever 48. The extremity of the pawl 46 is interposed in the path of the upper end of a plunger 50 which carries on its lower end 70 a roller 51 which is adapted to run over a raised member or cam bar 52 (see Figs. 1 and 2). The cam bars 52 are suitably disposed at predetermined points along the route of the vehicle and slightly in advance 75 of the tracks or cam bars 53, which are laterally spaced from the tracks or projections 52 to adapt them to engage the arm or lever 54 (see Fig. 4). The cam bars 52 maintaining the plunger 50 in raised position until cam bar 53 operates the lever 54. The lever 54 is carried by a stub shaft 55 which is journaled within a boss 56 carried by the housing 30. On the inner end of the shaft 55 is mounted a lever arm 57 80 which carries a cam block 58 which is adapted to engage the roller 59 journaled in the end of the reciprocable bar or lever 48. A pin 60 which projects laterally from the arm 57 projects into a yoke 61 which is 90 resiliently mounted upon a rod 62. The cam bars 52 and 53 are suitably disposed adjacent the terminals of the different zones of travel, so that as the vehicle approaches a given zone the pawl 46 is first elevated 95 by the plunger 50 after which the reciprocable lever 48 is operated to effect an angular displacement of 45° to the contact wheel, thereby making the circuit or breaking the same as the case may be. It will be seen 100 therefore, that it will be impossible to effect the circuit making or breaking operation without the prior actuation of the pawl 46 into position to engage the ratchet wheel 44. The plunger 50 will therefore be retained in an upward position by cam bar 52 while the contact wheel is being moved.

The operation of the controlling mechanism will now be readily understood. Suppose for example, that the vehicle is approaching a tunnel or subway zone of travel. First the plunger 50 is raised by the cam bar 52 and retained in elevated position until the lever arm 54 is engaged by the cam bar 53, causing the displacement of the reciprocating bar 48, and causing the insulating contact which under the conditions mentioned, will be in engagement with the fixed contact 31, to be displaced therefrom and a conducting contact introduced in its place. Immediately a current passes from the trolley line through line wire 9 to the contact 31, thence to the hub 33 which is mounted in the housing 30, and thence to the contact 32 to which the wire 11 is connected. As a consequence, the illuminating system is energized throughout. On the other hand, as soon as the vehicle reaches

the far end of the tunnel or subway, similarly spaced cam bars 52' and 53' will similarly actuate the contact wheels to break the circuit and thereby deenergize the illuminating system. At night or where the vehicle travels continually in a subway or tunnel, the switch 21 may be thrown into circuit closing position to maintain the energization of the illuminating system.

10 I claim:

1. The combination with a vehicle, of a trolley line wire, a storage battery carried by said vehicle, a system of lights, another system of lights, suitable connections for including said systems of lights in circuit with said trolley line wire, means operated at predetermined points along the route of said vehicle for successively making and breaking said circuit connections, and means for connecting said other system of lights in circuit with said storage battery.

2. The combination with a vehicle, of means carried thereby for illuminating the same, said means being capable of successive energization and deenergization, and means automatically operated at predetermined points of travel for energizing said illuminating means on entering a predetermined zone of travel and for deenergizing the illuminating means on leaving said zone of travel.

3. The combination with a vehicle, of a trolley line wire, a storage battery carried by said vehicle, a system of lights, another system of lights, suitable connections for including said systems of lights in circuit with said trolley line wire, means operated at predetermined points along the route of said vehicle for successively making and breaking said circuit connections, and means for connecting said other system of lights in circuit with said storage battery, said means for connecting said other system with said storage battery being provided with a branch having a manually operated switch for cutting out of circuit the make and break means operated at predetermined points along the route of the vehicle.

4. The combination with a vehicle, of illuminating means carried thereby, means for deriving power from without said vehicle for energizing said illuminating means, other means carried by said vehicle for energizing said illuminating means, and means depending upon the movement of said vehicle for controlling the energization of said illuminating means, said controlling means being rendered operable at predetermined points along the route of said vehicle.

5. The combination with a vehicle, of illuminating means carried thereby, means depending upon the movement of said vehicle for energizing said illuminating means, and means depending upon the movement

of said vehicle for deenergizing said illuminating means, said energizing and deenergizing means including interengaging elements arranged along the route of the vehicle and carried by said vehicle respectively.

6. The combination with a vehicle, of illuminating means carried thereby, means depending upon the movement of said vehicle for energizing said illuminating means, and means depending upon the movement of said vehicle for deenergizing said illuminating means, said energizing means including an element carried by the vehicle, and an element disposed along the route of said vehicle and adapted to cooperate with the element carried by said vehicle.

7. The combination with a vehicle, of illuminating means carried thereby, means depending upon the movement of said vehicle for energizing said illuminating means, and means depending upon the movement of said vehicle for deenergizing said illuminating means, said deenergizing means including an element carried by the vehicle and another element disposed along the route of said vehicle and adapted to actuate the element carried by said vehicle.

8. The combination with a vehicle, of illuminating means carried thereby, means depending upon the movement of said vehicle for energizing said illuminating means, and means depending upon the movement of said vehicle for deenergizing said illuminating means, said energizing means and said deenergizing means including an element carried by the vehicle and another element disposed along the route of said vehicle and adapted to actuate the element carried by the vehicle.

9. The combination with a vehicle provided with an illuminating system of a controlling instrumentality for rendering said illuminating system operative during one zone of travel and inoperative during another zone of travel, and means for actuating said instrumentality, said means being adapted to be actuated at predetermined points along the route of said vehicle.

10. In a car, a trolley line wire, main car illuminating lights, an automatic make and break device for controlling the energization of said lights, suitable connections for including said trolley line, lights and make and break device in circuit, emergency lights, a storage battery normally connected to said emergency lights, means for breaking the trolley line circuit, and means for completing the storage battery circuit.

11. In a car, a trolley line wire, main car illuminating lights, an automatic make and break device for controlling the energization of said lights, suitable connections for including said trolley line, lights and make and break device in circuit, emergency

lights, a storage battery normally connected to said emergency lights, means for breaking the trolley line circuit, and means for completing the storage battery circuit, the last said means being arranged to cut out said automatic make and break device.

12. In a car, positive and negative lines, main illuminating lights, a conductor provided with a switch connecting said lights to said positive line, emergency lights, a connection extending from said emergency lights to said main lights, a conductor for connecting said emergency lights to said negative line, and a storage battery interposed between said negative line and emergency lights.

13. In a car, positive and negative lines, main illuminating lights, a conductor, provided with a switch connecting said lights to said positive line, emergency lights, a connection extending from said emergency lights to said main lights, a conductor for connecting said emergency lights to said negative line, a storage battery interposed between said negative line and emergency lights, an automatic make and break device included in the connection extending between the main lights and emergency lights,

and a short circuiting branch provided with a switch for cutting out said make and break device.

14. In a car, positive and negative line wires, main lights, emergency lights, means for connecting said line wires, main lights and emergency lights in circuit, means for making and breaking said circuit at predetermined points along the route of said car, a storage battery, and means for connecting said emergency lights in circuit with said storage battery independently of said main lights.

15. In a car, positive and negative line wires, main lights, emergency lights, means for connecting said line wires, main lights and emergency lights in circuit, means for making and breaking said circuit at predetermined points along the route of said car, a storage battery, and means for connecting said emergency lights in circuit with said storage battery independently of said main lights, and said circuit making and breaking means.

WILLIAM S. MENDEN.
